CLAIM

The ornamental design for a watchband, as shown and described.

DESCRIPTION

FIG. 1 is a perspective view of a watchband, showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof;

FIG. 9 is an enlarged view of portion of FIG. 1 thereof; and,

FIG. 10 is an enlarged view of portion of FIG. 1.

The dot-dash broken lines depict the boundaries of the enlargements that form no part of the claimed design.

1 Claim, 10 Drawing Sheets(56)
